DESIGN FOR A BRACELET

Leopold D. Kline, Kew Gardens, N. Y.

Application February 19, 1948, Serial No. 144,592

Term of patent 14 years

(Cl. D45—4)

To all whom it may concern:

Be it known that I, Leopold D. Kline, a citizen of the United States, and a resident of Kew Gardens, county of Queens and State of New York, have invented a new, original, and ornamental Design for a Bracelet, of which the following is a specification, reference being had to the accompanying drawing, forming part thereof.

Fig. 1 is a perspective view of a bracelet showing my new design, and

Fig. 2 is a perspective view of the opposite side thereof showing the bracelet in an open position.

I claim:

The ornamental design for a bracelet, as shown.
LEOPOLD D. KLINE.
